UNITED STATES PATENT OFFICE.

RUDOLF LOEB, OF JENKINTOWN, PENNSYLVANIA.

SEWING-MACHINE.

1,267,566.

Specification of Letters Patent.

Patented May 28, 1918.

Application filed December 31, 1913, Serial No. 809,799. Renewed July 11, 1916. Serial No. 108,713.

To all whom it may concern:

Be it known that I, RUDOLF LOEB, a citizen of the United States, and a resident of Jenkintown, Montgomery county, Pennsylvania, have invented certain Improvements in Sewing-Machines, of which the following is a specification.

My invention relates to sewing machines of the type employed to lay embroidery 10 stitches, being more particularly related to machines of the type for effecting the formation of eyelet embroidery. In the making of eyelets, it may be desired to form round eyelets; substantially "oval" eyelets, or 15 eyelets pointed at one end and joining a semi-circular portion at the opposite end, and the object of my present invention is to provide improved mechanism for accomplishing this result.

20 In a companion application filed December 31, 1913, Serial No. 809,798, I have shown mechanism capable of producing the several forms of eyelets, and the mechanism forming the subject of my present invention is designed for the same purpose; 25 though somewhat different in construction and mode of operation.

In each instance, a holding device is provided for the goods and while in the instance of the companion application longitudinal movement is imparted to the fabric holder in the formation of the substantially straight sides of the "oval" eyelets; in the 30 present instance the finishing of the straight sides of such eyelets is accomplished by swinging the fabric holding member in the arc of a circle; a pivotal mounting for the arm carrying the fabric holding member being set at one side of the machine at a 35 point substantially at right angles thereto and in the plane of vibrative movement of the needle.

As in the companion application referred to, the machine for applying stitches to the 40 edges of the preformed apertures is substantially like that disclosed in my pending application filed January 14, 1913, Serial No. 741,948, and the means whereby I am 45 enabled to stitch the edges of the preformed apertures to effect the eyelet embroidery is in the nature of an attachment to said machine. It will be understood, however, 50 that such attachment may, with slight modi-

fications, be applied to other sewing machines of a type substantially like the one 55 illustrated in the accompanying drawings.

These and other features of my present invention are more fully described herein-after, reference being had to the accompanying drawings, in which:

Figure 1, is a side elevation of a machine for making either round or elongated eyelets, showing the mechanism forming the subject of my present invention for accomplishing this purpose;

Fig. 2, is a plan view of the same;

Fig. 3, is an end elevation;

Fig. 3^a, is a view illustrating a detail of my invention;

Fig. 4, is a detached perspective view of 70 the operating mechanism;

Fig. 5, is an enlarged view, partly in section, of the fabric holding and moving member, and

Figs. 6, 7 and 8, are views illustrating 75 successive stages in the formation of the "oval" eyelets.

As before noted, the machine to which the attachments forming the subject of my invention have been applied is of a character 80 substantially similar to that of my companion application (or that forming the subject of my pending application, Serial No. 741,948,) and the needle operating mechanism is controlled by a series of cams and 85 adjusting elements as disclosed therein; all of which is substantially as follows:

In the drawings, 1 represents the frame of the machine and 2 the head containing the means for effecting vertical reciprocation of 90 the needle bar 3 which, in this type of machine, is pivotally mounted so as to be capable of vibrating under the action of suitable mechanism. In this connection, it may be noted that the mechanism for imparting 95 vertical reciprocation to the needle bar is old and well known in the art, and no extended reference thereto is thought to be necessary herein. The needle bar carries a needle of any ordinary or usual type; indicated at 4, which may be secured to said bar by a set screw 5.

In the lower part of the head of the machine is an arm 6, pivoted at 7, and having a sleeve 8 encircling the said needle bar, and 100 through which said needle bar may slide

during its vertical reciprocation. Movement imparted to the arm 6 effects vibration of the needle bar, and for this purpose the following mechanism may be employed, 5 which mechanism includes means for adjusting or regulating the extent of such movement.

Suitably carried by the frame of the machine is a counter-shaft 10, having a gear wheel 11, which receives motion from a gear 12 on the main driving shaft 13 of the machine. On the opposite end of said counter-shaft is a cam 14, which engages a roller 15 carried by an arm 16 connected to a rock 10 shaft 17 suitably journaled in or on the frame of the machine, and having at one 15 end a substantially yoke-shaped lever 18, one end of which engages with a pin 19 adapted to slide in the head of the machine 20 and impinge upon the arm 8. The yoke-shaped lever is provided with adjustable screws 20 and 21 forming contact points; 25 said screws having lock nuts 22 whereby they may be retained in any predetermined adjusted position.

Return movement of the arm 8 when the roller carrying arm 16 is released from the action of the high side of the cam is imparted by means of a flat spring 23, suitably 30 connected to the head of the machine, and having an end 24 bearing against the said arm 8. Upon rotation of the countershaft 10, movement is imparted to the cam 14 and transmitted to the arm 8 for the purpose of 35 vibrating the needle-bar and its attached parts by the means just described; reverse movement of said needle-bar being accomplished by the spring referred to.

The extent of the movement of the needle-bar by the cam 14 and the roller arm 16 is 40 determined by the size of the said cam, while the position of the needle-bar, needle and presser foot with respect to the slot in the stitch plate, is determined by the adjusting 45 screws 20 and 21; one being set in and the other out, as the case may be, and the upper one, (indicated at 20 for instance) bearing upon the frame of the machine.

The arm or lever 16 is in two parts, hing- 50 edly connected together by a pin 16^a and held in operative condition by a pin 25^a slidably mounted in said arm or lever, which pin 25^a is in operative engagement with the end 55 25^b of a bell crank lever 25 which is pivoted to said arm or lever 16 at 26. When this pin 25^a is withdrawn, in the manner herein- 60 after described, the cam 14 may move the end of the lever 16 on the pivot pin 16^a without affecting the rock shaft 17.

60 I have provided means in the shape of a bell crank lever 25 pivoted at 26 to a projection carried by the lever arm 16, which bell crank lever is operatively connected to a rod, 65 in a manner hereinafter described, which rod is actuated by a knee-lift (not shown)

employed with this type of machine, under control of the operator. Operation of said knee-lift in a manner common to machines of this type stops the vibration of the needle; permitting it to reciprocate vertically and form tacking stitches in order to stop off the thread employed in the binding or edging of apertures in the fabric. These apertures are preferably preformed, and the means for holding and effecting stitching or 70 edging of the fabric at the marginal outlines or edges of these apertures may be described as follows:

The bed-plate 30 of the machine is recessed or apertured at 31, and adapted to 80 said recess or aperture is a plate 32. This plate carries means for holding the fabric; such means permitting complete or partial rotation of the fabric from a single axis in the plane of the vibration of the needle, 85 more particularly described hereinafter. The plate 32 rocks upon a stud 33 supported by a bracket 34 suitably attached to the bed-plate 30 of the machine, and extending outwardly from the same at right angles thereto. The plate 32 is pivotally mounted upon the stud 33 for slightly rocking or lateral vibration and carries a bracket 35, to which a lever 36 is pivoted at 37; one end of said lever being operatively connected to a post 38 carrying the fabric holding mechanism indicated at 39. The post is provided with a slot 40, to which the end of the lever 36 is adapted whereby rocking movement imparted to this lever will cause the fabric 90 holding mechanism to move vertically.

Movement is imparted to the said lever 36 by the following mechanism: Supported in suitable bearings 41 attached to the bed-plate 30 of the machine is a shaft 42, carrying an arm 43 lying in contact with an arm 44 carried by a shaft 45 supported in suitable bearings 46; one of which is carried by one of the bearings 41. Attached to the forward end of the shaft 45 is an arm 47, for engagement with a pin 48 carried by a lever 49. The lever 49 is pivotally mounted at 50 in a post 51 depending from the plate 34. The opposite end of the lever 49 is operatively connected to a rod 52 extending upward through the stud 33 and pivotally attached to the lever 36, at 53. A spring 55 surrounds the rod 52; tending to raise the lever 36, and maintain the fabric-holding element in its lowered position for operative 110 engagement with the fabric.

The shaft 42 carries a rod 56 having a knee-piece (not shown). When the operator desires to raise the fabric-holding element, she pushes against the knee-piece which 115 moves the rod 56 and causes the shaft 42 to rock or partially rotate. The arm 43, pressing upon the arm 44, rocking the shaft 45, brings the arm 47 in contact with the pin 48 of the lever 49, raising one end of the latter 120

and drawing down upon the connecting rod 52, causes the lever 36 to raise the fabric holding element.

The arm 43 has a pin 57 arranged to contact with the curved surface 58 of a lever 59 pivoted at 60 to a bracket 61 carried by the bed-plate 30 of the machine; the lever 59 having an extended forked end 62 embracing a vertically sliding rod 63 supported in suitable bearings attached to the frame 1 of the machine; such rod having an engaging portion in the shape of adjustable and locking nuts 64 and 65, and being supported by a spring 66. The downward pressure of the pin 57 against the lever 59 causes it to pull down on the vertically sliding rod 63 against the tension of the spring 66. This action effects movement of the bell-crank lever 25 and causes it to withdraw the pin 25^a and render inactive the arm or lever 16 operated by the cam 14, thereby stopping movement of the rock shaft 17 and its lever 18 controlling the length of the stitches. For this purpose 25 the rod 63 is provided with a projection 63^a which engages one end of said bell-crank lever 25 when said rod is lowered.

The vibration of the needle may be stopped by operating the knee-lift to the full extent and then the needle may reciprocate vertically to form tacking stitches in order to stop off the thread employed in the binding or edging of the apertures of the fabric.

35 Supported in suitable bearings 71, one of which is attached to one of the bearings 41, is a rock shaft 68 carrying an arm 69, having a chain 70 connected with suitable operating means, such as a foot treadle (not shown), under the control of the operator. Downward pull upon this chain will move the rock shaft 68 and move a forked arm 71 to withdraw from the plate 32 an indexing pin 72, thereby allowing the operator 40 to swing the plate 32 on the stud 33 to carry the goods with respect to the needle and permit the laying of stitches in a substantially straight line to obtain the desired result in making the eyelet.

50 The fabric-holding means is more clearly shown in Figs. 4 and 5, wherein it is seen to consist of a circular element 75, which receives a series of rings 77 and 78, properly secured together by clips 79 carried by the element 75; the ring 78 being channeled at 80 on its under side for the reception of a ring of rubber or similar material, indicated at 81, and being grooved on its upper side at 82 for the reception of balls 83 interposed between said ring 78 and a similarly formed grooved in the ring 77, thereby forming a ball-bearing and permitting ready rotary movement of the rubber-shod lower ring with respect to the rest of the structure.

The plate 32 is provided with a circular plate 84 disposed concentrically with respect to the rubber-shod foot plate or ring 78 of the fabric-holding means and being grooved for the reception of balls 85 whereby an anti-friction bearing between the same and the recess 86 in the plate 32 receiving the same is provided; said circular plate 84 being roughened on its upper surface and held in place by a central clamping plate 87, which may be secured by screws 88. This clamping plate and the plate 32 are provided with registering openings 89 for movement with respect to a fixed needle guide 90 projecting through the same and co-operating with the needle.

The member 77 of the fabric-holding means may be in the form of an undulatory annular ring, as in my companion application before referred to, so that springs 77^a 85 may be interposed between it and the element 75 to insure pressure upon the rubber ring or foot 81 for holding the fabric against the rotatable plate 84. Two or more springs may be employed, as may be desired, to insure proper tension upon the material being embroidered.

Upon examining Figs. 6, 7 and 8, it will be noted that the fabric as prepared for embroidery has a number of preformed apertures 95 therein, some of which are pointed at one end and join semi-circular portions at the opposite end, which apertures are to have their edges stitched or seamed. The fabric is held stretched in an ordinary tambour frame (not shown) commonly employed in embroidering machines, and this tambour frame is laid over the bed-plate of the machine; the fabric-holding means being raised to permit the proper positioning of the fabric beneath the same, and the operator then manipulates said tambour frame so as to bring the point *a* of the fabric, (see Fig. 6) directly opposite the plane of vibration of the needle; the plate 32 carrying the bracket which supports the foot being held by the pin 72. As soon as this position is determined, the pin is released, (in the manner described), and the operator grasping the plate 32 by hand moves the same to the right, 115 away from and out of control of said pin 72. The stitch-operating mechanism of the machine is then set in motion; the preliminary short stitches indicated at *a* being first placed, and then while the said needle is 120 vibrating to and from the operator, the bracket is slowly moved to the left, effecting the formation of the substantially parallel stitches on the upper edge of the aperture, as indicated in Fig. 6. As soon as the 125 point *a* is reached, the pin 72 automatically enters the aperture or recess in the plate 32, preventing further movement to the left of said plate and indicating that the stitching to that extent has ceased. The operator then 130

rotatively turns the fabric; a movement of which may readily be effected by reason of the holding means above described; the rubber pad on the under side thereof holding 5 the fabric against the turntable plate, and the two being movable with a minimum of friction owing to the ball bearings employed, which has the effect of stitching the semi-circular end, in the manner indicated in 10 Fig. 7, which brings the stitched portion to the condition and position shown in Fig. 8, and then by releasing the pin 72 and effecting further movement of the bracket to the left, the completion of the stitching around 15 the eyelet may be effected. The other apertures are stitched in a similar manner.

I claim:

1. In an eyelet forming machine, the combination of stitch forming means, a manually operable swinging member having a turntable, and rotatable fabric-holding means carried by said swinging member for co-operation with said turntable, said fabric-holding means being manually turnable 25 when the fabric is clamped between the same and the turntable.

2. In an eyelet forming machine, the combination of stitch forming means adapted to laterally vibrate in a single plane, a swinging plate laterally disposed with respect to the machine and in line with said stitch forming means, a turntable carried by said plate, rotatable fabric-holding means carried by said plate and manually operable 30 with respect to said turntable, and means for vertically moving said fabric-holding means.

3. In an eyelet forming machine, the combination of stitch forming means adapted 40 to laterally vibrate in a single plane, a swinging plate having a turntable, fabric-holding means carried by said plate and co-operating with said turntable, said plate being manually movable with the fabric-holding means, means for locking said 45 swinging plate in line with the vibrating stitch forming means, and means for releasing the locking device, said fabric-holding means being manually rotatable at the end 50 of the swinging movement of said plate.

4. In mechanism for forming eyelet embroidery, the combination of stitch forming means adapted to laterally vibrate in a single plane, a swinging plate, means for locking said plate, means for releasing the same, a turntable carried by said plate, and fabric-holding means carried by said plate 55 and co-operating with said turntable, said fabric-holding means being rotatable, and 60 said stitch forming means being adapted to vibrate during the swinging movement of said plate and the rotary movement of said fabric-holding means.

5. In mechanism for forming eyelet embroidery, the combination of stitch-forming

means adapted to laterally vibrate in a single plane, a swinging supporting member manually operable, means for locking said swinging member, means for releasing the same, rotatable fabric-holding means carried 70 by said swinging supporting member, said fabric-holding means being movable with the plate and rotatable with respect thereto, and said stitch-forming means being adapted to vibrate during the movement of said plate 75 and the fabric-holding means, an arm carried by the swinging plate, a lever pivoted to said arm and supporting the fabric holding means, a second lever beneath the swinging plate for actuating the first-named lever, 80 and means for actuating said second lever.

6. In an eyelet forming machine, the combination of vibrating stitch-forming means, a swinging supporting member manually operable, a turntable carried by said swinging member, rotatable fabric-holding means carried by said swinging member and co-operating with said turntable, yielding 85 fabric engaging means for said fabric-holding means, and friction producing means carried thereby for holding the fabric in contact with the turntable.

7. In an eyelet forming machine, the combination of laterally vibratile stitch-forming means, a manually operable swinging plate 95 having a turntable, rotatable fabric-holding means carried by said swinging plate, and a yielding fabric engaging means for said fabric-holding means rotatable with said turntable. 100

8. In mechanism for forming eyelet embroidery, the combination of laterally vibratile stitch-forming means, a swinging supporting member, means for rocking or oscillating said member, means for locking said member, means for releasing the same, fabric-holding means carried by said supporting member, said fabric-holding means including a spring-held lever and a vertically movable rotatable foot, means for vibrating 110 said stitch-forming means during the movement of said fabric-holding means, and friction producing means for the rotatable portion of said fabric-holding means. 115

9. In mechanism for forming eyelet embroidery, the combination of laterally vibratile stitch-forming means, an arm set at right angles to the machine, a swinging plate pivoted to said arm in the plane of vibration of said stitch-forming means, means for locking said plate, means for releasing the same, fabric-holding means carried by said plate, said fabric-holding means having a rotatable portion, means for vibrating said 120 stitch-forming means during the movement of said fabric-holding means and the swinging plate, and yielding fabric engaging means for the rotatable portion of said fabric-holding means. 125

10. In an eyelet-forming sewing machine, 130

- the combination of stitch forming means, a manually operable swinging member having a turntable, and rotatable fabric-holding means carried by said swinging member and arranged to be secured in coöperative engagement with said turntable.
11. In an eyelet-forming sewing machine, the combination of stitch forming means laterally vibrating in a single plane, a swinging plate laterally disposed with respect to the machine and in line with said stitch forming means, a turntable carried by said plate, rotatable fabric-holding means carried by said plate and arranged to be secured in coöperative engagement with said turntable, and means for vertically moving said fabric-holding means.
12. In an eyelet-forming sewing machine, the combination of vibrating stitch forming means, a bracket projecting beyond the base of the machine, a swinging plate having a turntable and pivoted to said bracket, fabric-holding means carried by said plate and coöoperating with said turntable, said plate being manually movable with the fabric-holding means, means for locking said swinging plate in line with the vibrating stitch forming means, and means for releasing the locking device, said fabric-holding means being manually rotatable at one end of the swinging movement of said plate.
13. In mechanism for forming eyelet embroidery, the combination of stitch forming means laterally vibrating in a single plane, 35 a swinging plate, a bracket for supporting said plate, means for locking said plate, means for releasing the same, a turntable carried by said plate, and rotatable fabric-holding means carried by said plate and arranged to be secured in coöperative engagement with said turntable; said stitch forming means being adapted to vibrate during the swinging movement of said plate and the rotary movement of said fabric-holding 45 means.
14. In mechanism for forming eyelet embroidery, the combination of laterally vibrating stitch-forming means, an arm set at right angles to the machine, a swinging 50 plate pivoted to the outer end of said arm in the plane of vibration of said stitch-forming means, a turntable carried by said swinging plate, and rotatable fabric-holding means carried by said plate and arranged 55 to be secured in coöperative engagement with said turntable.

In testimony whereof, I have signed my name to this specification in the presence of two subscribing witnesses.

RUDOLF LOEB.
